UNITED STATES PATENT OFFICE.

GEORGE FRED. BRINDLEY, OF NIAGARA FALLS, ONTARIO, CANADA, ASSIGNOR TO THE ROESSLER & HASSLACHER CHEMICAL COMPANY, OF NEW YORK, N. Y., A CORPORATION OF NEW YORK.

PROCESS OF FUSING MATERIALS.

No. 884,568.

Specification of Letters Patent. Patented April 14, 1908.

Application filed March 13, 1908. Serial No. 305,800.

To all whom it may concern:

Be it known that I, GEORGE FRED. BRINDLEY, a subject of the King of Great Britain, and a resident of Niagara Falls, Province of Ontario, Canada, have invented a certain new and useful Process of Fusing Materials, of which the following is a specification.

My invention relates to a process of fusing materials and has special reference to fusing materials of a corrosive nature without decomposing the same. Difficulties have been experienced in fusing certain materials of this class resulting from the tendency of the fused material to attack and destroy the containing vessel while at the same time the fused material is itself decomposed either from external causes or because of the contact with the walls of the containing vessel. In fact certain materials never have been successfully fused for these reasons. By my process I obviate these difficulties and successfully fuse the materials without in any way producing any chemical change in said materials as is the case in the ordinary electric furnace.

In the following I have described, in connection with the accompanying drawings, one means of carrying out my process, the features thereof being more particularly pointed out hereinafter in the claims.

In the drawings, Figure 1 is a side elevation, partly in section and partly diagrammatic, illustrating one form of apparatus designed to carry out my process and Fig. 2 is a cross sectional view of the apparatus shown in Fig. 1 along the line A—B.

Similar numerals of reference indicate similar parts throughout the several views.

In practicing my process I may use a suitable oblong vessel 1, made of any desirable material such as sheet copper, the walls of which may be cooled by a water jacket 2, to which access is had by means of pipes 3, 3, so that when the material in the vessel is fused a layer of unfused material is maintained between the walls of the vessel 1 and the fused material to act as a protector against corrosive action and as an insulator of the vessel from the current as hereinafter described. Electrodes 4, 4, of any desired material such as copper, are placed close to each end of the vessel 1 and connected to a suitable source 5 of alternating current through wires 6, 6, adjustable resistance 7 and switch 8. The elec-

trodes are preferably in the form of a broad 55 comparatively thin plate as is shown in the drawings, the backs and bottom edges thereof being protected from the walls of the vessel 1 by a layer of unfused material acting as an insulator therefrom, as described. The 60 material to be fused may be fed into vessel 1 by any suitable means as from a container 9 provided with a screw conveyer 10, carrying a gear 11, actuated by any convenient means so as to produce a constant or intermittent 65 feed as desired. As illustrated, the container 9 is vertically disposed and is adapted to discharge at a point slightly above the level 12 of the fused material 13 in vessel 1. A suitable resister 14, preferably of copper, 70 may be utilized for providing an initial connecting or conducting path from one electrode to the other through the unfused material. The fused material may be removed through spout 15 by tilting the vessel or by 75 permitting the fused material to overflow therethrough as desired.

In practicing my process through the means disclosed the vessel 1 is filled with the material to be fused, such as sodium peroxid, 80 a thin layer 16 of the same being interposed between the electrodes and the walls of vessel 1 for the purposes described. The resister 14 being inserted, the current is switched on of such strength that the resister 85 is heated to a point slightly above the melting point of the material to be fused. The heating of the resister causes the same to be surrounded by a mass of the fused material which now acts as a conductor itself. The 90 resister may now be removed if desired. The current density necessary varies with the size and material of the electrodes and the amount and character of the material to be fused, as is obvious to those skilled in the art. I have found that a current density of from 15 to 25 amperes per square inch of one immersed electrode surface is sufficient when fusing sodium peroxid and that it results in no decomposition of the peroxid as 100 long as the current is not interrupted. If the current density is higher than that stated so as to produce a degree of heat higher than slightly above the melting point of the material to be fused then the temperature of the bath adjacent to the electrodes is raised and they tend to become corroded. I have also discovered that if the flow of cur-

rent is interrupted the electrodes become corroded by the fused material in contact with them but as long as the current continues to flow this effect does not occur.

5 By feeding in fresh material either continuously or intermittently as described, a mass 17 of material is gradually formed in the bath which has the effect of displacing an equivalent amount of fused material which may be 10 removed through spout 15 and collected in any suitable receptacle. The formation of the mass 17 also has the effect of increasing the resistance in that portion of the bath in which it is formed, consequently if the voltage 15 between the electrodes be raised and the current density kept as before, a local heating takes place in that portion of the bath immediately surrounding mass 17 which is thus 20 gradually melted, being replenished as described.

By practicing the process in connection with the apparatus disclosed, regulating the current density and the rate and method of feeding as described, the material may be 25 fused without its attacking the walls of the containing vessel, decomposing the material, appreciably affecting the electrodes or contaminating the material to be fused by the 30 material of the electrodes or the containing vessel. Any contaminated fused material caused by the melting of the resister may be drawn off in the first discharge of fused material.

It is obvious that other apparatus may be 35 utilized in practicing the process and that the apparatus described may be widely varied without departing from the spirit of my invention, said apparatus disclosed being 40 illustrative only. I do not restrict myself to any particular apparatus or means, but

What I claim and desire to secure by Letters Patent is:—

1. A process of fusing corrosive material consisting in fusing without decomposing the same in the presence of air by passing an electric current between the electrodes in such manner that said current is of low density in the fused material adjacent to the electrodes and of high density adjacent to the material 50 to be fused and forming and maintaining a layer of unfused material on the inner walls

of the vessel containing the fused material between the electrodes and said walls.

2. A process of fusing corrosive material consisting in fusing without decomposing the same in the presence of air by the maintaining of an alternating current of low density in the fused material in contact with the electrodes and of a high density in that part of the bath where the unfused material is added 60 to the mass.

3. A process of fusing corrosive material consisting in fusing without decomposing the same in the presence of air, forming and maintaining an insulating layer of unfused material between the electrodes and the containing vessel and passing an alternating current through the fused material from one electrode to the other in such manner that said current is of low density in the fused 70 material adjacent to the electrodes and of high density adjacent to the material to be fused.

4. In a process of fusing alkali peroxids without decomposing the same the formation 75 and maintaining of an insulating layer of unfused alkali peroxid between the electrodes and the containing vessel, and the passing of an electric current through the fused alkali peroxid from one electrode to the other in 80 such a manner that said current is of low density in the fused alkali peroxid adjacent to the electrodes and of high density adjacent to the alkali peroxid to be fused.

5. In a process of fusing sodium peroxid 85 without decomposing the same the formation and maintaining of an insulating layer of unfused sodium peroxid between the electrodes and the containing vessel and the passing of an alternating current through the fused 90 sodium peroxid from one electrode to the other in such a manner that said current is of low density in the fused sodium peroxid adjacent to the electrodes and of high density adjacent to the sodium peroxid to be fused. 95

In witness whereof I have hereunto signed my name in the presence of two subscribing witnesses.

GEORGE FRED. BRINDLEY.
